Gordon C. Aymar INVENTOR.

BY Ramus Vogel his ATTORNEY.

UNITED STATES PATENT OFFICE.

GORDON C. AYMAR, OF NEW YORK, N. Y., ASSIGNOR TO DANYA, INC., OF NEW YORK, N. Y., A CORPORATION OF NEW YORK.

DESIGN FOR A JAR.

Application filed February 10, 1923. Serial No. 5,141. Term of patent 3½ years.

To all whom it may concern:

Be it known that I, GORDON C. AYMAR, a citizen of the United States of America, residing in the city of New York, in the county and State of New York, have invented a new, original, and ornamental Design for a Jar, of which the following is a specification, reference being made to the accompanying drawing, forming part thereof.

I claim:

The ornamental design for a jar, as shown.

GORDON C. AYMAR.
